UNITED STATES PATENT OFFICE.

JEROME W. SIMPSON, OF NEWARK, NEW JERSEY, ASSIGNOR TO WHEELER,
PARSONS & HAYES, OF SAME PLACE.

DESIGN FOR A JEWELRY-CHAIN.

SPECIFICATION forming part of Design No. 16,307, dated September 29, 1885.

Application filed April 27, 1885. Term of patent 7 years.

To all whom it may concern:

Be it known that I, JEROME W. SIMPSON, a citizen of the United States, residing at the city of Newark, in the county of Essex and State of New Jersey, have invented a new and original Design for Jewelry-Chains, of which the following is a specification.

In the accompanying drawings, Figures 1 and 2 are longitudinal views at right angles to each other of a piece of chain of my design. Figs. 3 and 4 are views of each of the two forms of links of which the design is composed.

A A and B B are the links, those A A being of elliptical profile of square transverse section and slightly twisted, and those B B, which alternate with A A, being of round transverse section doubled or folded, and also slightly twisted, and presenting two loops, a a, in one direction lengthwise of the chain, and two loops, b b, in the reverse direction lengthwise of the chain.

Portions c c of the doubled links B B are smooth and bright, and portions d d are roughened, the said bright portions c c presenting themselves at regular intervals in S-like curves along the center of the chain on either of the two faces of the chain which presents the faces of the links A A to view, as shown in Fig. 1, and the said roughened portions b b presenting themselves at the sides of the chain in the same view in salient arc-like curvatures. In the other two faces of the chain, one of which is shown in Fig. 2, the edges of the links A A present themselves at regular

intervals in S-like curves; the portions d d of the links B B present themselves in similar but shorter curves intervening between the said curves of A A, and the portions c c of the other links B B present themselves outward in salient arc forms on opposite sides of A A and d d.

What I claim, and desire to secure by Letters Patent, is—

1. The design for a jewelry-chain herein shown and described, the same consisting of a chain having the twisted elliptical links A A, presenting the S-like curvatures at their edges, and the double links B B, of which portions c c present themselves in S-like curves at regular intervals in the center of two opposite faces of the chain and in salient arc-like curves on the other two opposite faces, and portions d d present themselves in S-like curves on opposite sides of the S-like curves of the links A A.

2. The design for a jewelry-chain herein shown and described, consisting of a chain having the twisted elliptical links A A of square transverse section, and the double links B B of round transverse section, having bright portions c c, presenting themselves in S-like and salient arc-like curvatures, and roughened portions d d, presenting themselves in S-like curvatures intervening between corresponding curvatures of the links A A.

JEROME W. SIMPSON.
